UNITED STATES PATENT OFFICE.

FRANK N. KELSEY, OF FLORENCE, MASSACHUSETTS.

LOCK-HINGE.

SPECIFICATION forming part of Letters Patent No. 476,466, dated June 7, 1892.

Application filed October 5, 1891. Serial No. 407,814. (No model.)

To all whom it may concern:

Be it known that I, FRANK N. KELSEY, a citizen of the United States, residing at Florence, in the county of Hampshire and State 5 of Massachusetts, have invented new and useful Improvements in Lock-Hinges, of which the following is a specification.

This invention relates to improvements in lock-hinges which are especially designed for 10 the hinge-hanging of blinds, doors, and the like, the hinge embodying capabilities for exerting such spring action that the door or blind may be spring-retained in any of several positions, but of course capable of having its 15 position changed when forced with sufficient positive pressure to overcome the spring stress.

This invention has for its object the provision of a spring-hinge of the character set 20 forth which, first, owing to the form and arrangement of its parts, may be efficiently produced as to all parts thereof, excepting the spring, by casting, requiring no machine-finishing, and, secondly, is susceptible of having 25 the members thereof easily assembled or segregated, avoiding annoyances heretofore common in the application of certain forms of spring-hinges.

The invention consists in the combination 30 or arrangement of parts and the particular construction of certain of the parts, all substantially as will hereinafter more fully appear, and be set forth in the claims.

Reference is to be had to the accompanying 35 drawings, in which this invention is illustrated, Figure 1 being a front view of the hinge, shown as applied, for instance, for the hinge-support of a blind on a window-casing. Fig. 2 is a plan view of the same. Fig. 3 is a horizontal section of the same, taken on line 3 3, Fig. 1. Figs. 4, 5, and 6 are perspective views of the separated parts of the hinge; and Fig. 7 is an enlarged cross-sectional view or diagram through the spring-resisting part, as taken on the horizontal plane at the line 7 7 of Fig. 6.

The hinge consists of three parts or castings A B C and the flat spring D.

The casting A is the stationary part of the hinge and embodies a semi-cylindrical shell 50 or casing a, open at its rear side, provided with upper and lower partially-closing walls or heads b and lugs d, through which the fas-

tening-screws may be passed. The uniting and spring-resisting part C embodies a stud f, which, toward its bottom, is provided with 55 radial bearing or cam-like extensions g, the lower extremity of the stud entering for a bearing in the socket-aperture h in the bottom wall of the casting A, and the stud also projects upwardly above its radially-extended 60 portions through the recess i in the top wall of the casting, and, as shown, is pear-shaped or of other equivalent form in cross-section to spline-engage the hub j of the swinging hinge member B, which rests upon the top 65 wall of the said semi-cylindrical shell. The hub has a correspondingly-formed aperture j'. The opposite side walls of the casting-shell A, near the rear thereof, are apertured as at k, through which may be entered the flat 70 spring D to lie with its edges in a vertical plane at a proper distance back from the axis of the rotatable part C. The foot-plates or webs d', which are formed as continuations of the confinement-lugs d d, have cast thereon the 75 stops m for confining the spring against end-wise displacement after the same has been placed or sprung into the position shown and the parts of the hinge are assembled. The borders of said apertures k maintain the 80 spring against any transverse displacement.

The casting or part B comprises, in addition to the hub j, which has in substance a spline or key engagement with the rotatable and uniting part C, the bracket-arm n and 85 the confinement-plate o, through which to screw the said member b to the blind or other part, which is to be movably or hinge supported. The hub j of the part B rests upon the top of the said casing comprised in the 90 member A.

It will be noticed that the aperture i in the top of the semi-cylindrical casing (see Fig. 5) extends to the rear open side of said casing, and it will also be noticed with reference 95 to Fig. 7 that the stud at its part which is provided with bearing extensions g is at one side (in said view shown as the rear or upper side) of less radial extension from the axis of the stud than at the other sides. This may 100 be seen by noting the course of the concentric circle in the diagram, Fig. 7, with reference to the faces of the several projections g. Now in the assemblment of the parts before

the member B is connected and before the spring has been put in position across the rear opening in the casing member the part C is applied relative to the part A by having its lower shaft portion entered into the socket h, the upper shaft portion being passed into the recess i from the rear. Care is exercised so that the least prominent of the extensions g, as explained, are toward the open side of the casing member. The spring is now put into position, and the member B, by being inverted, may be used as a wrench to force the shaft C around for a quarter or a half rotation, so that the more prominent of the extensions 15 g are in bearing upon the spring.

The inversion of the member B to act as a wrench is to permit the part thereof which is offset from the end hub to pass by the lugs d at the upper part of the casting A. Of course 20 other means for turning the shaft may be employed; but that included in the hinge member B is always at hand and practical for the purpose.

The assemblage of the parts, especially the 25 part C with the one A, is by reason of the features of construction set forth readily performed, and may be done at the factory, and in the application of the hinge by the user of course no difficulty will be experienced in connecting the movable hinged member b to the 30 other parts, his utilization of the device in no way requiring the displacement of the spring, and thus annoyance heretofore experienced in the setting up of spring-hinges is under the 35 present invention done away with. Of course it will be apparent that the spring acting on the oblate portions of the intermediate bearing part between the ends of the shaft f will tend to hold the shaft part against rotational 40 movement, and consequently the blind, door, &c., against swinging or vibrating, and yet the door may be swung when sufficient force is intelligently applied thereupon to secure the deflection of the spring, as an extension g 45 has its impingement against the face thereof.

I claim—

1. A hinge one member of which consists of a hollow casting or shell with apertures k k in the opposite side walls thereof and a stud 50 mounted vertically and rotatably thereon, one portion of which is projected through and above the upper wall of the shell, another

portion of the said stud being contained within the shell and provided thereat with outward extensions and intermediately thereof less prominent sections, a flat spring supported by the borders of said apertures and in a position to be intermediately thereof impinged upon by the said stud extensions, and the other member of the hinge having a fixed 60 engagement with the upwardly-projected portion of the stud, substantially as described.

2. In a hinge, the combination, with a casing or shell, open at its rear side and having upper and lower walls, the latter having the 65 socket h and the upper wall being provided with the recess i, which extends to the rear open side of the shell and the opposite side walls of the shell having the apertures k, and confinement-lugs, as d, of a stud having between its ends the extensions g g with intermediate depressions and said stud having its lower portion bearing in said socket h and its upper portion extended through said aperture i and beyond the top of the casing, and 70 the flat spring extended across the rear side of said chambered shell and held against transverse displacement by the borders of said apertures k, the movable hinge member G, comprising the arm which at its extremity rests upon the top of the chambered hinge member and has an engagement with said stud, and one or more stops for preventing endwise movement of the spring, substantially as described.

3. In a hinge, the combination, with the casing, open at its rear and having upper and lower walls, the lower wall having the socket h and the upper one being formed with a recess i, which extends to the rear open side of 90 the casing, of a stud having between its ends radially-projecting extensions g g with intermediate depressions, the portion of the stud comprising such features being less extended at one side of the axis than the others, the 95 spring extending across the chamber in said shell relative to the said extension-provided stud, substantially as described, and the movable hinge member connected to the stud, substantially as and for the purposes set forth.

FRANK N. KELSEY.
